UNITED STATES PATENT OFFICE.

SAMUEL McD. ROBERTSON AND FREDERICK C. DYER, OF TORONTO, ONTARIO, CANADA.

WRENCH.

1,352,729.

Specification of Letters Patent. Patented Sept. 14, 1920.

Application filed October 13, 1919. Serial No. 330,416.

To all whom it may concern:

Be it known that we, SAMUEL McD. ROBERTSON and FREDERICK C. DYER, of the city of Toronto, in the county of York, Province 5 of Ontario, Canada, have invented certain new and useful Improvements in Wrenches, of which the following is a specification.

This invention relates to wrenches with adjustable jaws of the type commonly known as monkey wrenches, and our object 10 is to devise a wrench easily adjustable with one hand and which is therefore much more convenient for use by one-armed men than the ordinary types of adjustable wrench.

15 We attain our object by means of the constructions hereinafter described and illustrated in the accompanying drawings in which—

Figure 1 is a longitudinal section of our 20 improved wrench;

Fig. 2 a rear elevation of the same; and

Fig. 3 a section on the line *a—a* in Fig. 1.

In the drawings like numerals of reference indicate corresponding parts in the different figures.

1 is the movable jaw of the wrench, which is connected to the shank 2 which is flattened on at least one side, the preferable construction being to make it substantially rectangular in cross section. 3 is a threaded end 30 formed on the shank. 4 is the fixed jaw of the wrench, which is secured to the upper end of a tubular stem. The upper part 5 of this stem is flattened to form a guide for the flat sided shank 2, while the lower part 6 is cylindrical. This shape is readily given to the stem by suitably deforming a piece of tubing.

Fitted within the cylindrical part of the 40 stem is a tubular nut 7 internally threaded to engage the threaded end 3 of the shank 2. A sleeve 8 is fitted over the cylindrical portion of the stem and is suitably secured to the lower end of the tubular nut, as, for example, by means of a pin 9 driven through 45 suitable holes in the parts. The lower part of the tubular nut is preferably of increased diameter so as to come flush with the outer surface of the cylindrical portion of the shank, meeting the lower edge of the shank 50 with a shoulder. This shoulder takes the endwise strain due to pressure tending to force the jaws of the wrench apart.

To prevent endwise movement of the sleeve 8 relative to the tubular stem, we 55 form an annular groove 10 in the outer surface of the cylindrical portion 6 of the shank and thread through the sleeve 8 a screw 11, the end of which engages in the 60 groove.

From the construction described, it will be seen that the wrench is very simple in construction and can be made with a minimum of machine work. Further, as the adjustment is entirely through the sleeve 8, 65 which forms the grip of the wrench, it is very easy to adjust the spacing of the jaws with one hand to suit the nut with which the wrench is to be engaged. We prefer to form comparatively fine serrations 12 on the 70 movable jaw and to form a pair of deep transverse V-shaped grooves 13 in the fixed jaw. We find that with this arrangement the wrench can be used as a pipe wrench and is better adapted than a wrench with 75 flat faced jaws to operate on nuts the sides of which have become rounded or otherwise damaged.

What we claim as our invention is:—

In an adjustable wrench, the combination 80 of a movable jaw; a flat sided shank therefor; a threaded end on the shank; a fixed jaw; a tubular stem to one end of which said jaw is fixed, the tube adjacent said end being flattened to guide the flat sided shank, 85 its end remote from the fixed jaw being cylindrical; a tubular nut fitting within the cylindrical part of the tubular stem and engaging the threaded end of the shank; a sleeve fitted over the cylindrical portion of 90 the stem and having a driving engagement with the outer end of the tubular nut, and a connection between the sleeve and the cylindrical portion of the tubular stem preventing longitudinal movement of one or 95 the other, but permitting a movement of rotation.

Signed at Toronto, Canada, this 27th day of September 1919.

SAMUEL McD. ROBERTSON.
FREDK C. DYER.
